DOOR LATCH

Guy A. Wellman, Geneva, Ohio, assignor to The Champion Hardware Company, Geneva, Ohio, a corporation of Ohio

Application June 4, 1940, Serial No. 338,760

6 Claims. (Cl. 292—172)

The present invention relates to door latches, more particularly screen door latches, and has for its objects the provision of a novel, simple, and reliable door latch which can be readily installed with common tools and with a minimum of cutting and fitting.

The invention resides in certain details of construction and combinations and arrangements of parts, and further objects and advantages thereof will be apparent to those skilled in the art to which the invention relates from the following description of the preferred embodiment described with reference to the accompanying drawing in which similar reference characters designate corresponding parts and in which:

Fig. 1 is a side elevational view of a door provided with a door latch embodying the present invention;

Fig. 2 is a sectional view approximately on the line 2—2 of Fig. 1;

Fig. 3 is a sectional view on the line 3—3 of Figs. 1 and 5, with portions shown in elevation;

Fig. 4 is a view similar to Fig. 3, but showing the latch bolt in retracted position;

Fig. 5 is a sectional view on the line 5—5 of Fig. 3; and

Fig. 6 is a sectional view on the line 6—6 of Fig. 3.

Referring to the drawing, the reference character A designates a door provided with a door latch embodying the present invention. The door latch shown comprises a cylindrical casing 10 having a retractable latch bolt 11 slidably supported in the forward end thereof and continuously urged into a projected position by a compression spring 12 interposed between a shoulder formed by the rearwardly extending, reduced shank 13 of the latch bolt 11 and a member 14 projecting through a slot 15 formed in the latch bolt proper. The forward end of the bolt 11 is beveled as at 16 so that the latch bolt will be moved inwardly as the beveled portion engages the striker portion of a keeper when the door is closed. The keeper per se forms no part of the present invention and is not herein shown or described. Suffice it to say that the keeper may be of any suitable construction as is well understood in the art.

The latch bolt 11 is adapted to be retracted by two members 17 and 18 which, to some extent, resemble a longitudinally split sleeve having openings 19 on opposite sides which provide clearance for the knob shaft 20 which extends transversely through openings in the side of the casing 10 and is rotatably supported in the escutche-

on plates 21 and 22 secured to the front and rear of the door by screws 23 in the usual manner. Opposite ends of the knob shaft 20, which is square, as is the usual case, are provided with suitable knobs 25 and 26 of any desired form. The members 17 and 18 are moved relative to each other upon rotation of either of the knobs by a gear 27 having a square aperture through which the knob shaft projects, the teeth of which engage within suitable slots 28 which form the equivalent of gear racks in the members 17 and 18.

The forward ends of the members 17 and 18, that is, the left-hand ends as viewed in Figs. 3 and 4, are provided with inwardly extending projections or tongues 30 and 31, respectively, which project into the slot 15 in the shank 13 of the latch bolt 11 from opposite sides of the latch bolt. When the latch bolt is projected, the projections 30 and 31 are positioned side by side in the slot 15, see Fig. 6, and are interposed between the member 14, previously referred to, and the rear wall 32 of the slot 15. The rear ends of the members 17 and 18, that is, the right-hand ends as viewed in Figs. 3 and 4, are provided with inwardly extending projections or tongues 33 and 34, respectively, which lie side by side, see Fig. 5, when the bolt is projected and the members 17 and 18 in the position shown in Fig. 3. The members 17 and 18 are continuously urged towards the left, as viewed in Figs. 3 and 4, by a light cone-type compression spring 35 interposed between an inwardly directed flange 36 on the rear end of the casing 10 and a disk member 37 slidably supported in the casing 10 and engaging the rear ends of the members 17 and 18.

The operation of the door latch is as follows: When either the knob 25 or the knob 26 is turned to rotate the knob shaft 20 and in turn the gear 27, the members 17 and 18 are moved relative to each other longitudinally of the casing 10. The direction in which the members 17 and 18 are moved depends upon the direction in which the knob shaft is rotated. Assuming that the knob shaft 20 is rotated in the counterclockwise direction, as viewed in Figs. 3 and 4, the member 17 is then moved towards the left, compressing the spring 12 through the medium of the projection or tongue 30 and the member 14. Simultaneously the member 18 is moved towards the right, retracting the latch bolt 11 by the engagement of the projection or tongue 31 on the member 18 with the rear wall 32 of the slot 15 in the shank 13 of the latch bolt. This movement of the latch bolt further compresses the spring 12 and the re-

sult is that the spring 12 is subjected to a double action which is highly desirable in devices of the character here involved, as will be hereinafter more specifically pointed out. The rearward movement of the member 18 compresses the light cone-type spring 35 interposed behind the member 37 but this spring is relatively light as compared with the spring 12 and, if desired, can be omitted altogether. When the bolt 11 has been fully retracted, the parts are substantially in the position shown in Fig. 4. Upon release of the knob, the bolt will be projected and the parts returned to the position shown in Fig. 3 under the action of the springs 12 and 35.

In the event that the knob shaft is rotated in a clockwise direction, as viewed in Figs. 3 and 4, the operation of the door latch will be the same as mentioned above except that the members 17 and 18 will be moved in opposite directions, in which event the member 17 will effect the withdrawal of the bolt through the medium of the projection or tongue 30 formed integral therewith and the spring 35 will be compressed by the member 18. The fact that the projections or tongues 30 and 31 extend into an elongated slot in the bolt permits the latch bolt to be retracted upon engagement with a striker plate or either of the members 17 and 18 to be moved forwardly without otherwise interfering with the operation of the device. When the latch bolt 11 is retracted by the engagement of the beveled portion 16 thereof with the striker portion of the keeper, the rearward movement of the bolt is resisted by a single action of the spring 12, with the result that the latch bolt will operate more satisfactorily on light doors than would be the case if movement of the latch bolt was resisted by the same force, irrespective of the manner in which it is retracted. When the latch bolt is retracted by engagement of the beveled surface 16 with the striker portion of the keeper, the only frictional resistance which it is necessary for the spring to overcome in returning the latch bolt to protracted position is that existing between the latch bolt proper and the casing 10, whereas when the latch bolt is retracted by rotation of either of the knobs, the friction of the entire mechanism must be overcome in restoring the latch bolt to protracted position, thus a heavier spring action is desired when the latch bolt is retracted by rotating one of the knobs than when it is retracted by the striker plate. As shown, part of this additional spring force is obtained from the spring 35, which is conical in shape, primarily for the purpose of saving space.

In applying the door latch of the present invention to a door, it is merely necessary to drill two holes, one into the side of the door large enough to receive the casing 10 with a snug or forced fit, and the other at right angles to the first for the reception of the knob shaft. If desired, the first hole can be counterbored slightly to receive an outwardly extending flange 38 formed integral with the front end of the casing 10 which limits the distance that the casing 10 can be forced into the hole. When the knob shaft 20 is in position, forward movement of the bolt 16 under the action of the springs 12 and 35 is limited thereby and by the members 17 and 18. In order to maintain the bolt 11, the members 17 and 18 and the gear 27, etc., in assembled relationship when the knob shaft 20 is removed, as for example, while the door catch is being applied to a door, provision is made for preventing rotation of the bolt assembly including the mem-

bers 17 and 18 in the casing 10 and for limiting the forward movement of the bolt 11 relative to the casing 10. As shown this means comprises a pin 39 fixed in the bolt 11 and projecting into a longitudinal slot or opening 40 in the casing 10 but other suitable means may be employed. The projecting end of the pin 39 does not extend far enough through the slot 40 to interfere with the free operation of the bolt 11. When the knob shaft 20 is removed, the spring 35 maintains the pin 39 in engagement with the front end of the slot 40 and the proportions or constructions are such that under these circumstances the aperture through the gear 27 is in alignment with the apertures in the casing 10 through which the knob shaft normally projects. These features of the present invention greatly facilitate the installation of the door latch because otherwise the parts would become disassembled during installation unless very carefully handled and difficulty would be encountered in aligning the aperture in the gear 27 with the openings in the casing 10.

The preferred embodiment of the present invention shown also comprises means for preventing rotation of the knob shaft 20, thus making it impossible to open the door, in the form of a plate 41 slidably supported on the underside of the inside escutcheon plate 22 and provided with a keyhole aperture 42, the upper cylindrical part of which is large enough to permit free rotation of the knob shaft while the lower portion is adapted to engage the knob shaft and prevent rotation thereof. The plate 41 is adapted to be raised and lowered by a knob 43 fixed thereto, the shank of which projects through a suitable slot in the escutcheon plate 22. When the plate 41 is in its down position, the knob shaft 20 projects through the cylindrical part of the keyhole aperture 42 but when the plate 41 is in its up position, the knob shaft 20 projects through the lower square portion of the keyhole aperture and rotation of the knob shaft is prevented. The fact that the plate 41 is moved upwardly to lock the knob shaft against rotation prevents the plate 41 from being accidentally moved into locking position by vibration or jar, such as may be caused by slamming of the door. A small depression 44 in the escutcheon plate 22 adapted to project either above the plate 41 or through the upper part of the opening 42, depending upon whether the plate is in its down or up position, helps to retain the plate in either of its two operating positions.

From the foregoing description of the preferred embodiment of the invention, it will be apparent that the objects heretofore enumerated have been accomplished and that I have provided a new and improved door catch which is simple in construction, reliable in operation and which can be readily installed with a minimum amount of effort. While the preferred embodiment of the invention has been described with considerable detail, I do not wish to be limited to the particular construction shown which may be varied within the scope of this invention and it is my intention to cover hereby all adaptations, modifications and variations thereof which come within the practice of those skilled in the art to which the invention relates.

Having thus described my invention I claim:

1. A door latch of the character described comprising a casing, a latch bolt slidably supported in said casing, a plurality of members within said casing movable relative to each other and to said casing for retracting said latch bolt, means in-

cluding a shaft extending transversely through said casing and provided with a hand grasp for simultaneously moving said members in opposite directions longitudinally of said casing, a compression spring interposed between said latch bolt and the forward ends of said members whereby said spring is compressed by the forwardly moving member upon actuation of the first named means, and means for operatively connecting said latch bolt with the forward ends of said members whereby said latch bolt is retracted by the rearwardly moving member upon actuation of said first named means.

2. A door latch of the character described comprising a cylindrical casing, a latch bolt slidably supported in said casing, a plurality of relatively movable members within said casing for retracting said latch bolt, means including a shaft extending transversely through said casing and provided with a hand grasp for producing relative movement between said members longitudinally of said casing, a compression spring interposed between said latch bolt and the forward ends of said members, means for operatively connecting said latch bolt with the forward ends of said members, an abutment adjacent to the rear end of said casing, and a compression spring interposed between the rear ends of said members and said abutment.

3. A door latch of the character described comprising a casing, a latch bolt slidably supported in said casing and having a longitudinally extending slot therein, a member comprising two relatively movable parts slidably supported within said casing for retracting said latch bolt, means including a shaft extending transversely through said casing and provided with a hand grasp for simultaneously moving said parts of said member in opposite directions longitudinally of said casing, and a compression spring interposed between said latch bolt and the forward end of said member, said member having a portion extending into said slot for operatively connecting said latch bolt with said member.

4. A door latch of the character described comprising a casing, a latch bolt slidably supported in said casing, a plurality of relatively movable members within said casing, means in-

cluding a shaft extending transversely through said casing and having a hand grasp for simultaneously moving said members in opposite directions longitudinally of said casing, a compression spring interposed between said latch bolt and the forward ends of said members, projections on said members, and said latch bolt being recessed for operatively connecting said latch bolt with said members.

5. A door latch of the character described comprising a cylindrical casing, a latch bolt slidably supported in said casing and having a longitudinally extending slot therein, a plurality of relatively movable members within said casing for retracting said latch bolt, means including a shaft extending transversely through said casing and having a hand grasp for producing relative movement between said members longitudinally of said casing, a compression spring interposed between said latch bolt and the forward ends of said members, projections on said members extending into said slot for operatively connecting said latch bolt with said members, and a compression spring interposed between the rear of said members and the rear end of said casing.

6. A door latch of the character described comprising a cylindrical casing, a latch bolt slidably supported in said casing and having a longitudinally extending slot therein, a plurality of relatively movable members within said casing for retracting said latch bolt, means including a shaft extending transversely through said casing to the rear of said bolt and having a hand grasp for producing relative movement between said members longitudinally of said casing, a compression spring interposed between said latch bolt and the forward ends of said members, projections on said members extending into said slot for operatively connecting said latch bolt with said members, a compression spring interposed between the rear of said members and the rear end of said casing, and means for limiting the forward movement of said latch bolt when said transversely extending shaft is removed from said casing.

GUY A. WELLMAN.
